BICYCLE HANGER

Alexander L. Generalis, 249 S. 10th St., Philadelphia, Pa.
19107, and Michael C. Roberto, 534 Rockland Ave.,
Mamaroneck, N.Y. 10543

Filed Apr. 7, 1972, Ser. No. 242,291

Term of patent 14 years

Int. Cl. D8—08

U.S. Cl. D8—235

FIG. 2

FIG. 3

FIG. 6

FIG. 4

FIG. 5

FIG. 1 is a perspective view of a bicycle hanger in accordance with the instant invention. A portion of a wall and of a bicycle are shown in phantom lines for purposes of illustration.

FIG. 2 is a top plan view thereof.

FIG. 3 is a bottom plan view thereof.

FIG. 4 is a front elevational view thereof.

FIG. 5 is a rear elevational view thereof.

FIG. 6 is a side elevational view thereof. The other side appears exactly the same and opposite.

We claim:

The ornamental design for a bicycle hanger, as shown and described.
